Attorney

UNITED STATES PATENT OFFICE.

DANIEL W. SHEPHERD, OF POCATELLO, IDAHO.

CONCENTRATING SURFACE.

1,405,018.

Specification of Letters Patent. Patented Jan. 31, 1922.

Application filed September 7, 1920. Serial No. 408,691.

To all whom it may concern:

Be it known that I, DANIEL W. SHEPHERD, a citizen of the United States, residing at Pocatello, in the county of Bannock and 5 State of Idaho, have invented certain new and useful Improvements in Concentrating Surfaces, of which the following is a specification, reference being had to the accompanying drawings.

10 This invention relates to concentrating belts, tables and other surfaces over which material to be concentrated travels, and particularly to a particular manner of forming the surface of the concentrating belt, table 15 or the like.

The general object of my invention is to provide an improved concentrating surface wherein the rubber, canvas or other surface of the concentrating table or concentrating 20 belt or apron is covered with sawdust held in place by means of cement; this sawdust acting to hold the concentrates while permitting the silt, sand and other light particles to be washed down and off the belt 25 or table.

Other objects will appear in the course of the following description.

My invention is illustrated in the accompanying drawings, wherein:—

30 Figure 1 is a longitudinal sectional view of a concentrating surface constructed in accordance with my invention;

Figure 2 is a top plan view of the concentrating surface.

35 My invention may be applied to concentrating decks or tables in mills or to concentrating belts or to sluice boxes. I have illustrated my invention as applied to a concentrating belt, but it is to be understood

40 that I do not wish to be limited to the illustrated application of this surface. In the drawings, 10 designates a belt or layer which may be of rubber, canvas or any other suitable fabric, and which is coated with an initi-

45 ally soft and thin coating of rubber cement, designated generally 12, and sprinkled over this cement, when soft, is sawdust 13, the sawdust being very thickly scattered upon the surface of the fabric, so that the fabric

50 is practically covered with the sawdust and the face of the fabric roughened thereby. This belt or layer covered with sawdust as

described has been particularly designed for use on "Snake River" gold bearing sands which contain fine flour gold, and this has 55 been found extremely successful. All of the gray sand and almost all of the slit flows over this surface without being caught by the sawdust, but the black concentrates containing gold and other valuable metals are 60 caught, the sawdust making a rough surface and having pitholes and rough edges which hold the concentrates.

In order to get the concentrates from the sawdust, the concentrates are rinsed off with 65 water, or the belt, where a concentrating belt is used, may be run through a hutch containing water. It will be understood, of course, that where a belt is used, the mixed material is delivered upon the belt, which 70 has sufficient inclination so that the material with the water will tend to flow towards the lower end of the belt, the belt moving upward contrary to the flow of the water. The flow of the water separates the lighter 75 slimes and sand and discharges them at the lower end, while the fines and concentrates will be held by the sawdust. The concentrates are washed off in the usual box into which the belt dips. 80

I claim:—

1. A concentrating element having a surface over which the ore is adapted to flow composed of a roughly granular fibrous material adhering to the element and covering 85 the same.

2. A concentrating element having a surface over which the ore is adapted to flow composed of fabric and a covering adhering thereto composed of comminuted, relatively 90 rough particles of fibrous material.

3. A concentrating element over which the ore is adapted to flow consisting of a layer of fabric, cement covering the face of said fabric, and sawdust distributed 95 closely over the fabric and caused to adhere thereto by the cement.

4. A concentrating surface over which the ore is adapted to flow having a layer of sawdust thickly distributed thereon and ad- 100hering thereto.

In testimony whereof I hereunto affix my signature.

DANIEL W. SHEPHERD
